UNITED STATES PATENT OFFICE.

SAMUEL COHN, OF NEW YORK, N. Y.

DESIGN FOR A LABEL-BLANK.

42,930.

Specification for Design.

Patented Aug. 27, 1912.

Application filed May 27, 1911. Serial No. 629,953. Term of patent 7 years.

To all whom it may concern:

Be it known that I, SAMUEL COHN, a citizen of the United States, residing at the city of New York, borough of Manhattan, in the county and State of New York, have invented a new, original, and ornamental Design for a Label-Blank, of which the following is a specification, reference being had to the accompanying drawing, forming part thereof, in which is shown a face view of a label-blank incorporating my said design.

In said drawing the label blank is shown as of rectangular outline having a slightly ribbed border. At each inner corner of said border is arranged a crescent-shaped ornament of conventionalized foliage. The opposite inner horizontal ends of the crescent-shaped ornament are connected by curved members which meet at the center of the label blank at the top and bottom thereof, and the opposite vertical ends of said crescent-shaped ornament are connected together by vertical members.

At about the center of the label blank is

arranged an elliptical field which extends entirely across said label blank, and serves to produce a horizontal panel above and below said elliptical field. Upon the elliptical field is disposed a wreath composed of leaves and berries, which wreath is ornamented at its lower middle portion by a bow of ribbon, the flowing ends of which extend to the opposite sides of the label blank. Within said wreath is displayed snowclad landscape comprising a house, and outbuildings, partially surrounded by trees and shrubbery. In the foreground is shown a fence and some shrubbery. The barren trees and branches, together with the snow-drifts, suggesting a winter landscape.

I claim—

The ornamental design for a label blank, as herein shown and described.

SAMUEL COHN.
